UNITED STATES PATENT OFFICE.

SANFORD A. MOSS, OF LYNN, MASSACHUSETTS, ASSIGNOR TO GENERAL ELECTRIC COMPANY, A CORPORATION OF NEW YORK.

GOVERNING MECHANISM FOR COMPRESSORS AND EXHAUSTERS.

1,265,482.

Specification of Letters Patent.

Patented May 7, 1918.

Application filed March 31, 1916. Serial No. 87,961.

To all whom it may concern:

Be it known that I, SANFORD A. Moss, a citizen of the United States, residing at Lynn, county of Essex, State of Massachusetts, have invented certain new and useful Improvements in Governing Mechanism for Compressors and Exhausters, of which the following is a specification.

The present invention relates to governing mechanism for compressor or exhauster sets, especially those of the centrifugal type in which the admission of motive fluid to the prime mover of the set is controlled by a governing or regulating means which is responsive to changes in a condition of the gas being handled. This governing or regulating means may be, for example, a means for maintaining constant suction or constant pressure, or a means for maintaining constant volume.

The object of the invention is to provide an improved arrangement in which the governing or regulating means is rendered stable throughout the working range of the machine.

For a consideration of what I believe to be novel and my invention, attention is directed to the accompanying description and the claims appended thereto.

In the accompanying drawing Figure 1 is a diagrammatic view, partly in section, illustrating an embodiment of my invention, and Fig. 2 is a similar view of a second embodiment.

Referring to Fig. 1, I have here shown a turbine driven compressor adapted for use as an exhauster and in which the governing or regulating means is responsive to the suction produced by the compressor. 5 indicates a compressor which may be of any suitable type. In the present instance a centrifugal compressor is indicated having an inlet conduit 6 and an exhaust conduit 7. The inlet conduit may be connected, for example, to some suitable form of gas producing apparatus on which it is desired to maintain a substantially constant suction. 8 indicates a valve mechanism of suitable structure for controlling the admission of elastic fluid to the turbine 9, and 10 a fluid actuated motor for operating it, the motor being provided with a pilot valve 11. The fluid actuated motor is primarily under the control of a suction governor comprising a casing 12 in which is located an inverted

bell float 13 which is sealed by a suitable liquid, as indicated at 14. The interior of the bell float above the liquid seal is connected with the inlet conduit 6 by means of stand pipe 15 and conduit 16. The bell float is thus subjected to the pressure existing within conduit 6. The float 13 is connected to a lever 17 pivoted at 18 on the fixed support 19, by an adjustable rod 20. The left-hand end of lever 17 is connected to one end of a floating lever 21, the other end of which is connected by link 22 to a lever 23 pivoted at 24 to the stem of the valve mechanism 8 and at 25 to the stem of the pilot valve 11. This provides a usual form of follow-up device, as is well understood. 26 is a weight on lever 23 for biasing the lever toward a position to shut off the steam in case the link 22 or other connected parts should break. The floating lever 21 is connected between its ends to the governor lever 27 of governor 28 by a link 29, the link being connected to lever 21, preferably by a ball joint 29^a as shown. The right-hand end of lever 17 is provided with a depending arm 30 carrying an adjustable weight 31. The weight is made adjustable on the arm, for example, by being supported by a pin 32 inserted in one of the series of openings 33. 34 is a suitable dash-pot for steadyng the movements of the lever 17.

In operation the valve mechanism 8 is primarily under the control of the suction governor. If the pressure in conduit 6 decreases, indicating a falling off of the load, the bell float 13 will lower, pulling down the right-hand end of lever 17 and raising the left-hand end. This will rock the lever 21 on the ball joint 29^a causing it to lower the left-hand end of lever 23 and raise the right-hand end of it, thus moving the pilot valve upward. During this movement the lever 23 pivots at 24. Actuating fluid is thus admitted above the piston of 100 the fluid actuated motor 10 and the valve mechanism 8 is moved toward closed position. At the same time the lever 23 will pivot on rod 22 and the pilot valve will be moved downward along with the valve 105 mechanism, thus cutting off the admission of motive fluid to the motor 10. In case the pressure in the conduit increases, indicating an increase in the load, then the same action takes place, except in the opposite 110

direction, and the supply of motive fluid to the turbine is increased so as to take care of the increased load.

In connection with governing mechanisms of this general type; *i. e.*, those which are responsive to changes in a condition of the fluid handled, there is a tendency for them to over-regulate or "hunt." I have discovered that this can be eliminated by providing the governing mechanism with a stabilizing means which changes its effective action with changes in the load, and this is the function of the depending arm 30 and the weight 31. When the governor moves 10 the lever 17 the weight 31 moves on the arc of a circle having the pivot point 18 for its center. The arc is indicated by the line A. This movement brings the weight nearer to or farther from the pivot point 18 and hence varies its action on the bell float 13. For example, for the range of the governor 15 as shown, the weight will vary in distance from the point 18 in passing from no load to full load by an amount indicated by the distance between the two dot and dash lines 20 B and C. The arrangement is such that the weight increases its effective action on the governor with increase in the load. In the case of a suction governor, as shown, this 25 means that the suction decreases slightly with increase in the load. That is, at light load the suction is greater than at full load. Expressed in terms of pressure, it means that the pressure in the suction conduit increases slightly with the load. It will thus be seen that as the load increases the effective 30 action of the stabilizing weight 31 also increases since it is moved farther from the pivot point with each increase in load. By 35 this means I obtain stable governing for all loads within the range of the governor. The action is quite analogous to that of an ordinary speed governor whose weights assume slightly different positions in passing from 40 the no load to the full load position, and with which the speed decreases with increase in the load.

The speed governor 28 is normally inactive and for normal speeds the lever 27 and 45 pivot point 29^a are stationary. In case of excess speed, however, the governor 28 comes into service and assumes control of the turbine preventing any further increase in speed irrespective of the action of the suction 50 governor. In other words, the speed governor acts as a speed limiting device as distinguished from a governor which controls the speed at all times. The action of the speed governor 28 on the valve mechanism 8 is obvious and needs no further explanation.

A mechanism as just described, or a similar one, can be used as a constant pressure governor instead of a constant suction governor, as will be obvious, the only change

required being to adjust the leverage arrangement so that changes in pressure produce the opposite effect on the regulating mechanism to that which they do in the case of a constant suction governor. This will 70 be apparent when it is considered that with a constant pressure governor, increase in pressure means a decrease in load and vice versa, which is just opposite to that in the case of a constant suction governor. 75

Referring now to Fig. 2, my invention is shown as applied to a constant volume governor. 40 indicates a driving motor, as a steam turbine, having a valve chest 41 containing a suitable valve mechanism actuated 80 by a shaft 42 on which is fixed an operating arm 43. 44 indicates a part of the casing of a centrifugal compressor and 45 the intake conduit therefor. Located in the intake conduit is a float 46 that rises and falls with 85 increase and decrease in the rate of flow of air or gas through it. The float is mounted on a rod 47 that extends upwardly through the top of the casing and is connected to a tilting lever 48 which corresponds to lever 17 of Fig. 1. The tilting lever 48 is pivoted at 49 to a bracket 50 mounted on a suitable portion of the machine. Connected to the lever 48 is an arm 51 that is connected to the arm 43 of the regulating mechanism by 90 a rod 52. On the one end of the lever 48 is an adjustable weight 53 which may be moved along the lever 48 to set the mechanism for different flows, and on the other end is a depending arm 54 carrying a weight 100 55, these parts corresponding to the arm 30 and weight 31 of the mechanism shown in Fig. 1. The arm 54 is adjustable along the lever 48 and the weight 55 is adjustable on the arm 54. 56 is a suitable dash-pot for 105 steadying the movements of the mechanism. It will be understood that the valve gear for the turbine shown in Fig. 2 may comprise a suitable governor arranged after the manner of that shown in Fig. 1 and operating in the 110 same general manner.

The operation of the arrangement of Fig. 2 will be obvious from the description already given of Fig. 1. As the flow increases or decreases the float will assume a higher 115 or lower position in the intake conduit, thus tilting the lever 48 about its fulcrum 49. This will move the stabilizing weight 55 so as to bring it farther from or closer to the pivot 49 thus varying its effective action. 120

It will be seen that in each of the arrangements shown, the stabilizing weight may be set at various heights so as to give variable amounts of difference between the suction, or pressure, or flow (as the case may be) at 125 no load and at full load. With the stabilizing weight in its highest position there will be the least difference, but, of course, it follows that at the same time the governing will be the least stable. With the stabilizing 130

weight in its lowest position, there will be the greatest difference, but also the greatest amount of stability. In any particular case the adjustment will be such as to give the 5 stability desired.

In accordance with the provisions of the patent statutes, I have described the principle of operation of my invention, together with the apparatus which I now consider to 10 represent the best embodiment thereof; but I desire to have it understood that the apparatus shown is only illustrative, and that the invention can be carried out by other means.

15. What I claim as new and desire to secure by Letters Patent of the United States, is:—

1. The combination of a compressor, a prime mover for driving it, a regulator for the prime mover, a governor which moves 20 in response to changes in a condition of the fluid handled by the compressor, a lever having a depending arm rigidly connected thereto, said lever being moved by the governor, a weight carried by the depending 25 arm, and means connecting the lever to the regulator.

2. The combination of a compressor, a prime mover for driving it, a pivoted lever which is moved to regulate the admission of 30 motive fluid to the prime mover, a depending arm rigidly connected to the lever and carrying a weight, and means responsive to changes in a condition of the fluid being handled by the compressor for moving the 35 lever.

3. In a compressor set, the combination of a motor, a compressor driven thereby, regulating mechanism for the motor, and means for operating it comprising a pivoted 40 lever, means connecting the lever to the regulating mechanism, means for tilting the

lever in response to variations in a condition of the fluid being handled by the compressor, a depending arm rigidly connected to the lever, and a weight carried by the 45 arm.

4. In a compressor set, the combination of a motor, a compressor driven thereby, regulating mechanism for the motor, means for operating it comprising a pivoted lever, 50 means connecting the lever to the regulating mechanism, means for tilting the lever in response to variations in a condition of the fluid being handled by the compressor, a depending arm rigidly connected to the lever, and a weight carried by the arm; and a speed governor also arranged to tilt the 55 lever in case of excess speed.

5. In a compressor set, the combination of a motor, a compressor driven thereby, 60 regulating mechanism for the motor, and means for operating it comprising a pivoted lever, means connecting the lever to the regulating mechanism, a float connected to the lever, means for subjecting the float to the 65 pressure of the fluid on one side of the compressor, and a depending weighted stabilizing arm rigidly connected to the lever.

6. In a compressor set, the combination of a motor, a compressor driven thereby, 70 regulating mechanism for the motor, means for operating it comprising a pivoted lever, means connecting the lever to the regulating mechanism, an inverted bell float having a liquid seal, a rod connecting it to the lever, 75 a conduit connecting the interior of the float to the compressor, a depending arm rigidly connected to the lever, and a weight carried by the arm.

In witness whereof, I have hereunto set 80 my hand this 16th day of March 1916.

SANFORD A. MOSS.
